Primary Examiner — Robert M Spear*Assistant Examiner* — Darcey E Heflin(74) *Attorney, Agent, or Firm* — St Onge Steward Johnston and Reens LLC(57) **CLAIM**

The ornamental design for a guitar body, as shown and described.

DESCRIPTION

FIG. 1 is the front view of a guitar body in accordance with the new design;

FIG. 2 is a rear view thereof;

FIG. 3 is top view thereof;

FIG. 4 is a bottom view thereof;

FIG. 5 is a left side view thereof;

FIG. 6 is a right side view thereof;

FIG. 7 is a front perspective view of the guitar body with the environment removed for clarity of disclosure;

FIG. 8 a front perspective view showing my design within an environment thereof; and,

FIG. 9 is a rear perspective view showing my design within an environment thereof.

In the drawings, the broken lines showing portions of the guitar depict environment and form no part of the claim.

1 Claim, 4 Drawing Sheets(56)
